UNITED STATES PATENT OFFICE.

EMIL ZWAHLEN, OF NORTH BRADDOCK, PENNSYLVANIA.

COMBINATION BLIND AND CURTAIN SUPPORT.

1,425,160.

Specification of Letters Patent.

Patented Aug. 8, 1922.

Application filed May 11, 1921. Serial No. 468,464.

To all whom it may concern:

Be it known that I, EMIL ZWAHLEN, a citizen of the United States, residing at North Braddock, in the county of Allegheny and State of Pennsylvania, have invented certain new and useful Improvements in Combination Blind and Curtain Supports, of which the following is a specification.

This invention relates to window blind and curtain fixtures, and the objects thereof are to provide a device of the character stated, in a manner as hereinafter set forth, which may be readily attached to a window frame without the use of nails, screws, and the like, thereby preventing injury to the frame, which is simple in its construction and arrangement, strong, durable and efficient in its use, readily adjustable, attractive in appearance, and comparatively inexpensive to manufacture.

To the accomplishment of these and such other objects as may hereinafter appear, the invention consists of the novel construction, combination and arrangement of parts herein specifically described and illustrated in the accompanying drawing, wherein is shown an embodiment of the invention, but it is to be understood that changes, variations and modifications may be resorted to which come within the scope of the claims hereunto appended.

In the drawing forming a portion of this specification and wherein like numerals of reference designate corresponding parts throughout the several views:

Figure 1 is a perspective view of the window blind and curtain fixture, in accordance with this invention, secured to a window frame.

Figure 2 is an end view of the device.

Referring in detail to the drawing 1 denotes the body portion of the device attached to the window frame 2. The outer end of the body portion 1 is provided with a rearwardly extending flange 3, adapted to engage the outer edge of the frame 2.

The longitudinal edges of the body portion are formed to provide a pair of parallel grooved guide members 4 on the front face of the body portion 1. The guide members 4 extend beyond the inner end 5 of the body portion 1 and each of said members extend in the same plane throughout. A coupling plate 6, provided with a rearwardly extending flange 7 adapted to engage the inner

edge of the frame 2, is slidably mounted in the inner end of the guide members 4 which extend beyond the body portion 1.

The inner end of the body portion 1 is formed with a forwardly projecting lug 8 provided with a threaded aperture 9. The opposed end of the coupling plate 6 is likewise provided with forwardly projecting lug 10 formed with an aperture 11. A coupling screw 12 passes through the aperture 11 and threadedly engages the threaded aperture 9 of the lug 8. By tightening the screw 12 the flanges 3 and 7 will firmly engage the respective edges of the frame 2 and securely hold the body portion 1 to the frame 2. Each side of the coupling plate 6 carries a projection 13 extending in respective guide members 4 to facilitate the shifting movement of the plate 6 in the guide members 4.

A supporting plate 14 is slidably mounted in the guide members 4 and is adapted for horizontal adjustment on the body portion 1. The plate 14 is provided with a screw 15 for locking the former in the adjusted position on the body portion 1. The plate 14 is integrally formed with a forwardly projecting bracket 16, suitably apertured, as at 17, for the reception of a blind roller end. An arm 18 is riveted, as at 19, to the upper portion of the bracket 16, and has its outer end formed to provide the barrel 20, which extends at right angles with respect to the arm 18. A curtain pole bracket 21 is slidably mounted in the barrel 20. The rear end of the barrel 20 is formed with a slot 22, which extends approximately one-half the length of the barrel 20. The rear end of the curtain pole bracket 21 carries a pin 23, which engages in the slot 22 of the barrel 20, and limits the forward movement of the bracket 21 in the barrel 20.

By the use of my improved fixture the use of nails, screws, and the like, which are liable to injure or mar the window frame, are entirely eliminated, and the device may be readily attached to a frame of the ordinary construction and conveniently removed therefrom when desired.

What I claim is:

1. A fixture for the purpose set forth comprising a body portion having a flange at one end and further formed with a pair of grooved guide members, each of said guide members extending in the same plane throughout and further extending beyond

the other end of the body portion, a flanged coupling plate slidably mounted in the extended portion of each of the said guide members, and a coupling screw for adjustably connecting the coupling plate to the body portion.

2. A fixture for the purpose set forth comprising a body portion having a flange at one end and further formed with a pair of grooved 10 guide members, each of said guide members extending in the same plane throughout and further extending beyond the other end of the body portion, a flanged coupling plate slidably mounted in the extended portion of 15 each of the guide members, a coupling screw for adjustably connecting the said plate to the body portion, and a supporting element adjustably mounted in said guide members against the body portion.

20 3. A fixture for the purpose set forth comprising a body portion having a flange at one end and further formed with a pair of grooved guide members, each of said guide members extending in the same plane throughout and further extending beyond the other end of the body portion, a flanged coupling plate slidably mounted in the extended portion of each of the said guide members, a coupling screw for adjustably

connecting the said plate to the body portion, a shiftable supporting plate mounted in the guide members against the body portion, an arm connected with the supporting plate and provided with a barrel, and a curtain pole bracket adjustably mounted in said 35 barrel.

4. A fixture for the purpose set forth comprising a body portion having a flange at one end and further formed with a pair of grooved guide members, each of said guide 40 members extending in the same plane throughout and further extending beyond the other end of the body portion, a flanged coupling plate slidably mounted in the extended portion of each of the said guide 45 members, a coupling screw for adjustably connecting said plate to the body portion, a shiftable supporting plate mounted in the guide members against the body portion, an arm connected with the supporting plate 50 and provided with a barrel, and a curtain pole bracket adjustably mounted in said barrel and having means for limiting the outward movement of said bracket with respect to the barrel, and means for locking the supporting plate to said body portion.

In testimony whereof I affix my signature.
EMIL ZWAHLEN.
